2 Sheets-Sheet 2

Technical drawing of a device assembly, labeled 'FIG. 2.' at the top left. The drawing is divided into several sections by a vertical line and a horizontal line. The top section contains a rectangular component with a circular hole (10) and a horizontal slot (43). Below this is a larger rectangular component with a slot (11) and a small rectangular part (42) attached. The middle section contains a horizontal slot (38) and a circular component (32) with a hole (33). The bottom section contains a horizontal slot (24) and a circular component (25). To the right of the main assembly are several vertical components: a long thin rod (16), a vertical slot (17), a vertical slot (22), a vertical slot (41), a vertical slot (46), a vertical slot (10), a vertical slot (14), a vertical slot (15), and a vertical slot (26). Arrows indicate specific features: an arrow pointing to the left from the top of the vertical line is labeled '3'; an arrow pointing to the left from the bottom of the vertical line is labeled '3'; an arrow pointing to the right from the right side of the main assembly is labeled '10'; an arrow pointing to the right from the right side of the vertical slot (10) is labeled '14'; and an arrow pointing to the right from the right side of the vertical slot (15) is labeled '15'.

Technical drawing of a truss structure labeled FIG. 7-45 46. The truss is supported by vertical columns at the left and right ends. The left column is labeled 16 and 10. The right column is labeled 10. The top chord is labeled 19 and 20. The bottom chord is labeled 18. Internal members include 17, 43, 44, 21, and 23. A horizontal line labeled 22 is shown at the bottom right. The drawing is enclosed in a rectangular border with diagonal hatching.

CONCRETE STEP

Edward A. Rogge, Marinette, Wis.

Application December 9, 1941, Serial No. 422,291

2 Claims. (Cl. 72—96)

This invention relates to a step or stair construction, and more particularly to a precast concrete step or stair.

An object of this invention is to provide a stair construction which can be preformed in knock-down form and set up easily and quickly at the desired location.

Another object of this invention is to provide a stair construction wherein a tread is cast integral with a riser, and each tread at the rear thereof is formed with a locking lug for engagement with a succeeding riser.

A further object of this invention is to provide in a stair of this kind a removable plug for receiving a rail supporting post.

A further object of this invention is to provide a stair of this kind which is so constructed that it is self-supporting, so that it may be set up on the exterior or interior of a building at the desired location.

To the foregoing objects and others which may hereinafter appear, the invention consists of the novel construction, combination and arrangement of parts as will be more specifically referred to and illustrated in the accompanying drawings, but it is to be understood that changes, variations and modifications may be resorted to which fall within the scope of the invention as claimed.

In the drawings:

Figure 1 is a detail side elevation of a stair or step structure constructed to an embodiment of this invention.

Figure 2 is a top plan partly broken away of the structure.

Figure 3 is a sectional view taken on the line 3—3 of Figure 2.

Figure 4 is a sectional view taken on the line 4—4 of Figure 3.

Figure 5 is a perspective view of one of the combined tread and riser members.

Figure 6 is a fragmentary sectional view taken on the line 6—6 of Figure 3, and

Figure 7 is a fragmentary sectional view taken on the line 7—7 of Figure 6.

Referring to the drawings the numerals 10 and 11 designate generally a pair of vertically disposed or upright side members for supporting stair treads in the desired location with respect to a building. The two supporting members 10 and 11 are of like construction and each includes a horizontally disposed base member 12 which is preferably formed of concrete suitably reinforced by embedded metal elements or the like, and the base member 12 has cast integral

therewith a plurality of upright supporting members 13.

The supporting members 13 at the upper ends have formed integral therewith a horizontally disposed and forwardly extending tread supporting member 14. The tread supporting member 14 has the upper surface thereof disposed in parallel relation with the base 12 so as to support a tread in a horizontal position. Each tread supporting member 14 has formed integral therewith a depending downwardly and forwardly extending supporting member 15. The supporting member 15 is inclined to the vertical, and the first supporting member 15 is formed integral with the base 12 whereas succeeding supporting members 15 are formed integral with the tread supporting members 14 and the uprights 13.

A relatively thin panel 16 is disposed between 20 pairs of uprights 13 and adjacent tread supporting members 15. These panels 16 are provided in order to close the space between the uprights 13.

In order to provide a means whereby the two 25 side members 10 and 11 may be held in a vertical position, I have provided a pair of crossed or intersecting bracing members 17 and 18. The bracing members 17 and 18, shown more clearly in Figure 4, are each provided with flattened

30 angularly disposed opposite end portions 19 which are adapted to engage inwardly projecting bolts 20, which have the outer portions thereof embedded in the side members 10 and 11. A nut 21 is threaded onto each bolt 20 so as to tightly hold the bracing members 17 and 18 in operative position. The upright 10 at the rear portion thereof is formed with an inwardly projecting foot or base plate 22, and the side member 11 is also formed with an inwardly projecting base foot 23. The two feet 22 and 23 provide additional surface engaging means for the side members 10 and 11 to prevent these side members from sinking into the ground or other surface.

45 A lowermost combined tread and riser member generally designated as 24 is mounted on the forward or projecting end portions of the two base members 12. The combined tread and riser member 24 includes a horizontally disposed flat tread member 25 which engages on the upper side of the base members 12 forwardly of the foremost riser supporting or bracing member 15. The two base members 12 are each provided in their upper surface thereof with a V-shaped keyway or notch 26 within which a

V-shaped key 27, carried by and formed integral with the tread member 25, is adapted to engage.

The keys 27 are adapted to hold the lowermost tread member 25 against forward or rearward movement with respect to the base members 12. Each base member 12 at its forward end is formed with an inclined surface 28 which is inclined to the vertical, being inclined upwardly and rearwardly, and a depending riser member 29 is formed integral with the tread member 25 and is adapted at its rear face to abut against the inclined faces or ends 28 of the two base members 12.

The riser member 29 is formed with a vertically disposed forward side or face 30, and with an inclined rear side or face 31 which is disposed on an angle coincident with the inclination of the forward ends 28 of the base members 12. The tread member 25 adjacent the opposite end portions thereof is formed with openings 32 within which removable plugs 33 are adapted to engage. The plugs 33 may be formed out of concrete or the like, and are provided so that in the event the user of this stair desires to secure side rails thereto, the plugs 33 may be forced out from the tread 25, and a rail supporting post or the like may be secured at its lower end in the opening 32.

The tread member 25 at its rear edge is formed with a pair of rearwardly extending substantially L-shaped locking members generally designated as 34. The locking members 34 have a horizontal side 35 formed with the upper surface thereof disposed in downwardly offset relation with respect to the upper surface of the tread member 25, and the opposite or vertical side 36 of each locking member 34 extends upwardly above the upper surface of the tread member 25. The downward offsetting of the horizontal side 35 of each locking member 34 forms an upwardly opening slot or channel 37 within which the lower end portion of a succeeding riser is adapted to engage. The two locking members 34 are disposed inwardly from the opposite end portions of the tread member 25 a sufficient distance, so that these locking members 34 may engage against the inner sides of the upright members 10 and 11 and thereby hold the tread members 25 against endwise movement.

A succeeding combined tread and riser member 38 is adapted to engage the first tread supporting member 14 and the riser member 39 is adapted at its lower edge to engage in the two channels 37 formed by the locking members 34 and the rear portion of the tread member 25. A tread member 40 is formed integral with the riser 39 and rests upon the succeeding tread supporting member 14 following the tread member 25. The rear edge portion of the tread member 25 is formed with a forwardly offset edge portion 41 which forms an open slot between the rear edge of the tread 25 and the forward side of the succeeding riser 39. The slot 41 as shown in Figure 5 is disposed between the two lock members carried by the tread member 25 and is designated for the purpose of draining water at the rear of each tread. The combined tread and riser member 38 is formed with a pair of substantially L-shaped riser locking members 42 which are similar in every detail to the locking members 34. The combined tread and riser member 38 is similar in every detail to the combined tread and riser member 24, with the exception that the combined tread and riser member 38 does not have the key 27, and may or may not be formed with a removable plug 33.

It will be understood that there may be as

many of these combined tread and riser members as may be necessary. Preferably the uppermost combined tread and riser member 43 is similar in every detail to the combined tread and riser members 38, with the exception that the tread 44 of the uppermost tread and riser member 43 does not have the locking members 34 extending rearwardly therefrom.

The tread 44 may be provided with a pair of removable plugs 45 adjacent the opposite end portions thereof, so that if desired the plugs 45 may be removed in order to form openings 46 to receive rail supporting posts or the like. In the use and construction of this stair structure the two side members 10 and 11 may be constructed separately as individual units, and as many of the combined tread and riser members may be also precast to form the desired steps. The lowermost combined tread and riser member 24 is initially mounted on the two spaced apart base members 12 after the side members 10 and 11 have been secured together in upright position by means of the two bracing members 17 and 18. The succeeding combined tread and riser members 38 may then be mounted on the succeeding tread supporting member 14. These succeeding tread and riser members 38 will have the riser portions 39 thereof engaging in preceding lock channels, so that the succeeding combined tread and riser members will be held against movement relative to each other, and the lowermost tread and riser member 24 will not only be held against movement relative to the succeeding tread and riser member 38, but will also be held against forward or rearward movement relative to the two side members 10 and 11 by engagement of the keys 27 in the keyways 26.

The tread and riser members 38 at the rear edges are adapted to abut against the adjacent supporting members 15, and a pair of locking members 42 carried by each tread and riser member 38 will hold these latter members against endwise movement with respect to the side members 10 and 11. In like manner the locking members 34 will hold the lowermost combined tread and riser member 24 against endwise movement with respect to the side members 10 and 11.

This stair construction as hereinbefore stated may be precast in suitable forms constructed for that purpose, and can be easily and quickly set up in the desired location without the use of any plastic, concrete, or cement. By forming the combined tread and riser members as insertable units, these tread and riser members may be easily replaced in the event they become broken or otherwise damaged. A stair constructed according to this invention may be constructed at a considerably reduced cost, from an ordinarily solid concrete stair or step structure and at the same time will provide for the necessary expansion and contraction of the material under varying temperature conditions.

What is claimed is:

1. A precast self-sustaining stair structure comprising a pair of upright side members including a base, inwardly projecting feet extending from the rear portion of said base, and tread supporting means carried by the base, said tread supporting means comprising a series of stepped inclined supporting members carrying a series of stepped horizontal tread supporting members, combined tread and riser members seated on said tread supporting members, said combined tread and riser members comprising a wedge-shaped

downwardly tapering riser member and a horizontal tread member integrally formed therewith, said tread member having the central portion of its rear edge forwardly offset to provide a drain opening, a pair of spaced apart substantially L-shaped locking members carried by the rear edge of said tread member for engagement with the lower edge of the succeeding riser, and a pair of crossed brace members each extending from the upper rear portion of one of said upright side members to the lower rear portion of the other of said side members.

2. A self-sustaining precast stair structure comprising a pair of cast integral upright side members, each of said side members having a ground supported base member of a length substantially equal to the depth of the stair structure, a series of stepped horizontal supporting

members, a series of upwardly and rearwardly inclined uprights carrying the forward portion of said horizontal supporting members, means for supporting said uprights from said base member, an inwardly extending foot carried by the lower rear edge of said base member, a pair of crossed brace members extending from the upper rear portions of said side members to the opposite lower rear portions of said side members, and a plurality of combined tread and riser members carried by said horizontal supporting members with the rear face of the riser portion of said combined tread and riser member contacting the forward face of said inclined upright, each combined tread and riser member having a vertical front riser side and an upwardly and rearwardly inclined rear face abutting the inclined uprights.

EDWARD A. ROGGE.
